CLAIM

The ornamental design for an attachable ostomy pocket, as shown and described.

DESCRIPTION

FIG. 1 is a front elevation view of an attachable ostomy pocket showing my new design with an attachment strip separated for clarity;

FIG. 2 is a rear elevation view thereof;

FIG. 3 is a right elevation view thereof, the opposite side being a mirror image of the shown;

FIG. 4 is a top plan view thereof;

FIG. 5 is a bottom plan view thereof; and,

FIG. 6 is an isometric view thereof.
